UNITED STATES PATENT OFFICE.

GEREROSO DI GIACOMO AND LOUIS MELCHIORRI, OF PHILADELPHIA, PENNSYLVANIA.

SOUND-TRANSMITTING APPARATUS.

1,410,897.

Specification of Letters Patent. Patented Mar. 28, 1922.

Application filed March 16, 1921. Serial No. 452,794.

To all whom it may concern:

Be it known that we, GENEROSO DI GIACOMO and LOUIS MELCHIORRI, both citizens of the United States, residing at Philadelphia, in the county of Philadelphia and State of Pennsylvania, have invented certain new and useful Improvements in Sound-Transmitting Apparatus, of which the following is a specification.

10 Our invention relates to improvements in sound transmitting apparatus for talking machines and particularly those of a portable type.

The principal object of our invention is to provide in a portable type of talking machine provided with a boxed lid hinged to the body of the machine so that when in an open position said lid is on a horizontal plane with the top thereof, of an improved 20 sound transmitting apparatus, adjustably positioned on said lid, whereby the tone reproduction is taken directly from the needle, amplified through the single medium of the tone or sound arm as the sound passes 25 through the tapering turns and out a bell shaped terminus thereof, striking against the surface of said lid which lid thereby acts as a resounding chamber transmitting the sound vibrations to the open air; reproducing 30 the original sound with accuracy and preserving the clearness of the modulated solo tones and the virile harmony of the chorus or the orchestra.

A further object of my invention is to provide improved sound transmitting apparatus for talking machines which renders it unnecessary to employ a horn or cabinet construction.

40 A further object of the invention is to provide a construction in a device of the class described that is simple, durable and one that can be manufactured and sold at a reasonably low cost.

These objects and other advantageous ends 45 we attain by means of the mechanism hereinafter described, reference to be had to the accompanying drawings, in which:—

Figure 1 is a perspective view of our talking machine in playing position;

50 Figure 2 is a vertical sectional view of the tone arm employed;

Figure 3 is a transverse sectional view on the line 3—3 of Fig. 2, and

55 Figure 4 is a top plan view of the pyramidal cover for the cup on the lid of said

machine in which the spindle of the tone arm rests.

Like reference characters refer to like parts throughout the drawings.

Referring to said drawings in detail the 60 numeral 10 represents a portable case for a talking machine provided with the table or support 11 for a turn table 12 on which is positioned a disc record 13 in the conventional manner. A spindle 14 extends 65 through said turn table 12 and record 13 and motor means, (not shown) positioned within said case 10 and beneath said table 11 are employed to rotate said spindle 14, which in turn rotates the turn table 12 and the disc 70 13 thereon.

Said case 10 is also provided with the boxed lid or cover 15, hinged as at 16, so that when in an open position said lid is on a horizontal plane with the top of the 75 body portion of said case 10.

A swiveled, as at 17', tone arm 17 having the tapering turns therein as illustrated, is provided with the sound box 18 having a needle connection 19 for engagement with a record 13 on the turn table 12, as is common in machines of this character. Said case 10 is also provided with a handle 20 for carrying purposes and locking means 21 and 21' to secure the lid 15 to the body 85 portion of said case 10, when desired.

Admission is gained to a compartment beneath the table or support 11 in the case 10 by means of a hinged door 22. The tone arm 17 may be stored within this compartment when not in use.

The said tone arm 17 at its opposite extremity from the sound box 18 is bell shaped as at 23 and at the base thereof a longitudinal brace 26 is secured to threaded 95 bosses 28 and 29, provided on the interior of the base of said bell shaped portion 23 of said tone arm 17, by means of screws 30 and 31.

A spindle 24 fits loosely in a socket 35 100 provided on a boss 36 on the interior of the upper part of the bell shaped portion 23 of the tone arm 17, as illustrated: said spindle 24 extends downwardly through an opening 27 provided in the horizontal brace 105 26, thus preventing lateral displacement of said spindle 24. A pin 25 through said spindle 24 adjacent the inner side of said brace 26 prevents vertical displacement of said spindle 24.

The projecting end 32 of said spindle 24 is tapered and rests loosely in a socket or cup 33 provided in the lid 15, said cup extending through said lid and having a 5 pyramidal cover on the outer side of said lid and is secured on the inner side of said lid by means of screws 34 as illustrated particularly in Fig. 3. The said tone arm 17 is obviously readily removable from its 10 connection with the lid 15 without removal of the spindle 24.

In operation: The lid 15 is placed in an open position or on a horizontal plane with the body of the case 10 as illustrated in 15 Fig. 1; the spindle 24 is inserted in the socket 33 and the needle connection 19 is placed in engagement with the record 13. As said needle 19 follows the grooves or 20 indentations of said record 13, the tone arm to which it is connected follows, it being rotatable on the spindle 24. The sound vibrations from said record are transmitted through the sound box 18 and amplified by the tapering turns of said tone arm 17 and 25 pass out through the bell shaped terminus 23 thereof, striking against the surface of the lid 15 whereby they are transmitted to the open air. The spindle 14 may extend considerably above the surface of the turn 30 table 12 so that it may be utilized to hold records when the machine is not in use.

It will now be apparent that we have devised a novel and useful construction which

embodies the features of advantage enumerated as desirable in the statement of the 35 invention and the above description, and while we have in the present instance shown and described the preferred embodiment thereof which has been found in practice to give satisfactory and reliable results, it is 40 to be understood that the same is susceptible of modification in various particulars without departing from the spirit or scope of the invention or sacrificing any of its advantages. 45

Having thus described our invention what we claim as new and desire to secure by Letters Patent is:—

In a portable sound reproducing machine, a hinged lid for the casing of the machine, 50 said lid being adapted to be arranged in a plane parallel to the plane of the turn table of the machine, a tone arm, a spindle supporting one end of the tone arm, and a socket mounted in the lid with its inner 55 end substantially flush with the inner surface of the lid and its outer end projecting beyond the outer surface of said lid, said socket having a bore of substantial length to detachably receive and pivotally 60 support one end of the spindle.

In testimony whereof we affix our signatures.

GENERO SO DI GIACOMO.
LOUIS MELCHIORRI.
